AIR CIRCULATING ATTACHMENT FOR
HEATING RADIATORSClarence M. Woolley, New York, N. Y., assignor to
American Radiator Company, New York, N. Y.,
a corporation of New Jersey

Application September 26, 1935, Serial No. 42,236

3 Claims. (Cl. 257—137)

My present invention relates to thermal enhancing attachment for thermal radiators.

More particularly, my present invention is directed to an attachment constructed and arranged to be associated with a thermal radiator, heating or cooling, which may be of any standard type, the attachment including one or more motor-fan units, a casing for housing and supporting the same, the casing being provided with air ingress openings, the stated assembly when associated with the radiator being positioned lowerly of the thermal exchange surfaces of the radiator.

In preferred embodiments of my invention, each motor fan unit is unitarily assembled with the casing and most preferably resiliently supported by the casing, and means are provided for stationarily installing the embodiment relative to the radiator.

Advantageously, the air ingress openings are located in predetermined relation to the radiator, i. e. to the usual respective sections of the radiator, the remainder of the sides of the casing being imperforate, whereby during the stage of fan operation, the projected air transverse predetermined paths of flow over the thermal i. e. heating or cooling, exchange surfaces of the radiator.

Utilization of my invention, as appears, results in enhancing the output of thermal units delivered by any radiator of any given total heating radiating surface, and additionally increases the circulation, i. e. re-circulation, of the air of the room or other space served by the radiator.

Further features and objects of the invention will be more fully understood from the following detail description and the accompanying drawing, in which

Fig. 1 is a side elevation, partly broken away for the sake of clarity, of a preferred type of embodiment of my invention.

Fig. 2 is a sectional view on line 2—2 of Fig. 1. Referring to the drawing, at 10 is illustrated any suitable type of thermal radiator, heating or cooling, the proper thermal medium being supplied to the radiator. The specific radiator illustrated in Figs. 1 and 2 is of the sectional type, the sections being individually designated 10a and the spacings between the sections being designated 10b; a supply pipe is indicated at 11 having a conventional shut-off valve 12; the valve 13 indicates any suitable steam trap, connected in the return pipe 14.

The embodiment of my invention illustrated in the drawing comprises a casing, the front side portion 15a being provided with air ingress openings 16. In the particular type of embodiment il-

lustrated in the drawing, the material of the remainder of the sides of the casing, i. e. the opposite ends 15b, 15c, are imperforate. In the embodiment illustrated in the drawing, there is no rear side of the casing, but which may be supplied if desired. Air ingress openings may be supplied in the opposite ends 15b, 15c, if desired.

Housed within such casing are one or more motor-fan units, the specific embodiment illustrated in the drawing being equipped with two 10 motor-fan units, the motor being designated 17 and the fan 18.

Each motor-fan unit is unitarily assembled with the casing, instanced in the illustrated embodiment by mounting each motor-fan unit upon a plate 19, suitably secured to the casing, as, see Fig. 2, by attachment to a bracket 20, the fixed end of which is secured to or integral with the material of the front side 15a of the casing.

Desirably, the motor 17 is of the electrical type, and in precaution of possible leakage of electrical current, insulation, see 21, is interposed between the plate 19 and the bracket or extension 20.

Preferably, as shown, each motor-fan unit is resiliently supported, as by positioning the supporting plate 19 in spaced relation to the floor 22 of the room or other space served by the radiator 10, the opposing ends of the plate 19, see 19a, being supported in spaced relation to the floor 22 by 30 angled extensions or the like serving as feet. The supporting plate 19 in effect provides floor means for the casing, and is secured to the casing as by means of the bracket 20 extending upwardly within the casing and engaging, at the bottom, the 35 footing provided by the angled inward extension of the bottom of front wall 15a, note Fig. 2.

To safeguard against incidental displacement of the casing and the therein housed parts, particularly of the type of casing having a rear open side, I recommend a rod 23 or equivalent, passing from one end, 15b to the opposing end 15c, and suitably attached to the same, as by means of nuts 24 or equivalent.

In Figs. 1 and 2, the radiator is shown elevated 45 by pedestal-like members 25, which may be necessary or desirable to provide proper clearance under the radiator for the positioning of my attachment.

As appears from the embodiment of my invention illustrated in Figs. 1 and 2, the casing has an outer contour conforming to the configuration defined by the mutually spaced feet or pedestal-like members serving to support the thermal exchange surfaced elements of the radiator per se. 55

Embodiments of my invention, as now appears, serve to increase the rise of temperature of the air of the room or other space served by any given radiator, by reason of the air projected by the respective fans 18, 18 upwardly relative to the radiator assembly and in heating or cooling exchange relation with the heating or cooling surfaces of the radiator.

The motor of the one or more motor-fan units 10 may be controlled by manually operated means, such as a snap switch, indicated diagrammatically at 26; such electric switch 26 may be of the two or greater multiple speed. Such switch 26 may be of the thermostatic controlled type and 15 provide for one or more intermediate speeds, as well as full speed and off positions.

For varied speeds of rotation of the one or more fans, the path of flow of the projected air in thermal exchange relation with the thermal surfaces 20 of the radiator is extended more upwardly, as well as increasing the mean rate of re-circulation of the air of the room or other space served by the radiator.

Whereas I have described my invention by reference to specific forms thereof it will be understood that many changes and modifications may be made without departing from the spirit of the invention.

I claim:

1. An as article of manufacture, a device for 30 effecting circulation of air, said device comprising a portable assembly including a casing having panel walls provided with ports and an open top; footing secured to said casing and extending inwardly thereof, said footing being adapted to rest directly on a supporting surface; supporting means secured to the inner extension of said footing and extending upwardly within said casing; floor means secured to the upper part of said supporting means and extending substantially 35 horizontally above the level of said footing; foot means remote from said footing for supporting said floor means directly on said supporting surface; and one or more motor-fan units mounted on said floor means for drawing air through the

45

ports of said panel walls and discharging air through said open top of the casing.

2. As an article of manufacture, a device for effecting circulation of air, said device comprising a portable assembly including a substantially rectangular casing having panel walls and an open top, a longitudinal wall of which is ported; footing formed at the bottom of said longitudinal wall and extending inwardly longitudinally thereof, said footing being adapted to rest directly on a supporting surface; supporting means secured to the inner extension of said footing and extending upwardly within said casing; floor means secured to the upper part of said supporting means and extending substantially horizontally above the level of said footing; foot means remote from said footing for supporting said floor means directly on said supporting surface; and one or more motor-fan units mounted on said floor means for drawing air through the ports of said panel walls and discharging air through said open top of the casing.

3. As an article of manufacture, a device for effecting circulation of air, said device comprising a portable assembly including a substantially rectangular casing having an open top and a front longitudinal wall, end walls extending backwardly from said front wall, and reinforcing means connecting the free ends of said end walls, said front wall having its bottom bent inwardly to form a footing extending longitudinally of said casing, said footing being adapted to rest directly on a supporting surface; supporting means secured to the inner extension of said footing and extending upwardly within said casing; floor means secured to the upper part of said supporting means and extending substantially horizontally above the level of said footing; foot means remote from said footing for supporting said floor means directly on said supporting surface; and one or more motor-fan units mounted on said floor means for drawing air through the ports of said panel walls and discharging air through said open top of the casing.

CLARENCE M. WOOLLEY.
